UNITED STATES PATENT OFFICE

151,233

DESIGN FOR A COMBINATION PEN AND PENCIL

Gerald A. Goessling, Richmond Heights, Mo., as-
signor to Quick Point Pencil Co., St. Louis, Mo.,
a corporation of Missouri

Application September 17, 1947, Serial No. 141,449

Term of patent 14 years

(Cl. D74—24)

To all whom it may concern:

Be it known that I, Gerald A. Goessling, a citizen of the United States and a resident of Richmond Heights, in the county of St. Louis and State of Missouri, have invented a new, original, and ornamental Design for a Combination Pen and Pencil, of which the following is a specification, reference being had to the accompanying drawing, forming part thereof.

Fig. 1 is a front elevational view of a combination pen and pencil, showing my new design, the cap being shown mounted on the pen end of the body;

Fig. 2 is a front view, showing the cap mounted on the pencil end of the body; and

Fig. 3 is a side elevational view of the body and cap separated.

I claim:
The ornamental design for a combination pen and pencil, substantially as shown.
GERALD A. GOESSLING.
